UNITED STATES PATENT OFFICE.

JAMES HAMILTON MILLER, OF ARKANSAS CITY, KANSAS.

AUTOMATIC TANK-CLOSING DEVICE FOR OIL-BURNING LOCOMOTIVES.

1,233,898.

Specification of Letters Patent. Patented July 17, 1917.

Application filed July 7, 1916. Serial No. 108,089.

To all whom it may concern:

Be it known that I, JAMES H. MILLER, a citizen of the United States, and a resident of Arkansas City, in the county of Cowley and State of Kansas, have invented a new and Improved Automatic Tank-Closing Device for Oil-Burning Locomotives, of which the following is a full, clear, and exact description.

10 My invention relates to a means for controlling the oil outlet leading from the tender to the fire box of a locomotive.

An object of my invention is to provide means whereby to automatically close the 15 oil outlet in the tender by the throwing of the engineer's valve of the brake system to emergency position which is done when a wreck is imminent.

Other objects of the invention, as well as 20 its advantages, will appear as the description proceeds.

Reference is to be had to the accompanying drawings forming a part of this specification in which similar reference characters 25 indicate corresponding parts in all the views.

Figure 1 is a side elevation partly in section showing parts of a locomotive and tender equipped with my invention;

Fig. 2 is a sectional side elevation of the 30 invention and showing a portion of the tender;

Fig. 3 is a view given to illustrate a slight modification in the manner of taking the air from the engineer's valve to automatically effect the closure of the oil outlet in the tank, said view at the left showing a portion of the tank while the engineer's valve is shown diagrammatically in plan view;

Fig. 4 is a longitudinal sectional view on an enlarged scale of the attachment to the engineer's valve employed in the form shown in Fig. 3.

The oil box 10 of the tender is provided, 5 as usual, with an outlet 11, which has a suitable pipe connection 12 with the fire box 13 of a locomotive 14.

The valve stem 15 is disposed vertically in the tender and operated in a fitting 16 in the top 17 of the tender, the upper end of the stem being provided with a handle 18. At the lower end, the valve stem extends through a guide or cage 19 and is provided with a valve 20, there being a coil spring 21 embracing the valve stem and normally

tending to close the valve on its seat at the outlet 11.

Mounted on the top 17 of the tender is a cylinder 22, here shown as on a stand 22^a, bolted or otherwise secured to the tender. 60 Operating in the cylinder 22 is a piston 23, the cylinder having a cushion spring 24 therein at one end.

An air pipe 25 leads from the cylinder 22 in front of the piston 23 to the engineer's 65 valve, designated generally by the numeral 26, the construction and operation of which is well known and need not be described. The connection between the pipe 25 and the engineer's valve 26 is such that when the 70 valve is thrown by its handle 26^a to the emergency position, air will pass through said pipe to the cylinder 22 and thereby actuate the piston 23. The piston rod 27 extends from the piston 23, and outside of 75 the cylinder 22, said piston rod is provided with a lateral member 28 which receives a pin 29, said pin passing through a hole 30 in the member 28 and through a pinhole 31 in the valve stem 15. The head 29^a of 80 the pin 29 lies against the forward side of the member 28 so that when the piston rod 27 moves forwardly, it will engage the said head 29^a and withdraw the pin 29 from the pin-hole 31 in the valve stem 15, thereby 85 permitting the spring 21 to close the valve 20 to its seat, thus cutting off the outflow of oil in the box 10.

I provide a vent which also, is controlled by the movement of the piston, as follows: 90 In the top 17 is a vertically disposed fitting 32, the lower end 33 of which extends into the tank 10, and is formed with a vent-hole or holes 34. A tube 35 is slidable in the fitting 32 and provided with a suitable handle 95 35^a for depressing the same. The bore of the tube 35 is continued through the handle 35^a so that the said tube communicates with the atmosphere. Near the lower end, the tube 35 has a vent-hole or holes 36, adapted to be brought into register with the vent-hole or holes 34. Within the lower end 33 of the fitting 32 is a spring 37 within an inverted cup-shaped housing 38, disposed beneath the lower end of the tube 35. In 105 the fitting 32 are registering transverse pin-holes 39, there being similar registering pin-holes 40 in the tube 35.

When the tube 35 is depressed against the pressure of the spring 37 to bring the vent- 110

holes, 34, 36, into register, the pin-holes, 39, 40, will be brought into register for receiving a transverse pin 41 which maintains the tube 35 in the depressed position. The pin 41 is connected by a short length of chain 42 or equivalent connecting means with the piston rod 27, that is to say, preferably with the lateral member 28 of said piston rod. The arrangement is such that 5 the forward movement of the piston rod 27 to withdraw the pin 29 for releasing the valve stem 15, will also withdraw the pin 41, thereby permitting the spring 37 to raise its housing 38 and the tube 35 to take the 10 vent-holes 36 of said tube out of register with the vent-holes 34, thereby cutting off the possibility of oil escaping through said vent-holes in case the tender turns over and breakage of the fitting 32 and stem 15 occurs. In order to prevent the piston 23 and rod 27 from turning, and to brace the said piston rod, a bar 22^a is secured to the cylinder head and has guided engagement with the member 28 of the piston rod. The 15 guided engagement is effected in the present instance by producing a longitudinal slot 22^b in the bar 22^a through which slot the member 28 extends whereby to brace the piston rod against bending strains and prevent it from turning on its axis.

In order that the engineer, if he desires, may close the valve 20 without affecting the described vent, I provide a chain or like flexible element 43 extending from the engineer's cab to a connection with the pin 29, the connection being through the medium of an eye 29^b on the head 29^a of said pin.

In the usual construction of oil-carrying tenders also, there is provision made for receiving a measuring rod, there being provided for the purpose, a tube in the top of the tender in which the measuring rod is usually permitted to remain. In order that no oil may escape at this point, I provide 40 a plug 44 closing a tubular member 45 through which the measuring rod may be inserted. The measuring rod may be hung on any suitable hook, (not shown), in the engine cab, and the plug 44 removed whenever said rod is required to be used.

In Fig. 1, the pipe 25 directly taps the engineer's valve 26. In the form shown in Figs. 3 and 4, a cylinder 45 is secured by a bracket 46 or other suitable means, to the engineer's valve, here indicated by the character 26^b, the character 26^a indicating the handle. The pipe 25^a corresponding with the pipe 25 leads from one end of the cylinder 45. To direct air from the main reservoir A to the cylinder 45, the usual pipe *a* leading from the said reservoir to the engineer's valve has a branch 47 communicating as at 48 with the pipe *a* and leading at its other end to the side of the cylinder 45. 45 The pipe 47 supplying air to the cylinder 45

is always in free communication with the said cylinder, but communication between the cylinder and pipe 25^a occurs only when the engineer's valve is in the emergency position.

For commanding the pipe 25^a, a piston 49 is provided in the cylinder 45, the stem or rod 50 of which is provided with a valve 51 at the end thereof closing a port 52 leading from the cylinder to the pipe 25^a. A spring 53 coiled about the stem 50 abuts at one end against a pin 54 on said stem and at the other end against a partition 55, in said cylinder. The partition has air ports 56 therethrough leading to the one side of the piston 49 and said piston has an air port 57 therethrough of predetermined limited capacity through which air may pass when the device is not in operation, whereby to equalize the pressure at both 85 sides of the piston. An outlet port 58 is formed in the head 45^a of the cylinder in front of the piston 49, and lateral ports 59 lead from the port 58 to the atmosphere. A valve 60 controls the port 58, the stem 61 of which valve is formed with a head 62 adapted to be engaged by the handle 26^a of the engineer's valve when said handle is thrown to the emergency position, indicated in dotted lines Fig. 3, whereby to unseat 90 the valve 60 and permit the escape of air from in front of the piston through the ports, 58, 59. The stem 61 is slidable in a boss or boxing 45^b on the cylinder head 45^a. The head 62 has a resilient arm 63 thereon formed with a stud 64 which is adapted to move in a longitudinal groove 65 in the boss or boxing 45^b. Communicating with said groove is a depression or recess 66 to receive the stud 64 under the spring action 1 of the arm 63 when the valve 60 is unseated by the handle 26^a of the engineer's valve. A knob or other finger-hold 67 is provided on the arm 63 to disengage the stud 64 from the recess 66. A compression spring 68 is coiled about the valve stem 61 in a housing 69 formed in the boxing 45^b, said spring abutting at one end against a pin 70 on the stem 61 to normally seat the valve 60.

When the handle 26^a of the engineer's valve contacts with the head 62 and unseats the valve 60, the stud 64 will engage in the recess 66 and maintain the valve open. Air may freely escape from in front of the piston 49, the restricted port 57 serving to maintain excess of pressure on the back of the piston 49 so that the said piston will be moved outwardly and unseat the valve 60, thereby permitting air to pass to the pipe 25^a and to the cylinder 22 for moving the piston 23 as previously described.

It is to be understood that the tank devices shown in Fig. 3 are the same as in Figs. 1 and 2. The construction shown in Figs. 3 and 4, it will be seen, results in no

modification whatever of the usual construction of the engineer's valve, and the bracket 46 may be secured to the exterior of the valve or other adjacent support to dispose 5 the head 62 in position to be engaged by the handle 26.

Having thus described my invention, I claim as new, and desire to secure by Letters Patent:

- 10 In an oil-burning locomotive, an oil container having an outlet, a valve controlling said outlet, a valve-closing means, a cylinder, a piston in said cylinder, a piston rod

on said piston extending to the outside of the cylinder, a pin movable with said piston rod upon a forward movement of the piston, the said valve having a stem formed with a pin hole adapted to receive said pin, and means adapted to connect with the brake system of the locomotive to conduct 15 fluid to said cylinder for actuating the piston; together with manually controlled means connected with said pin and adapted to withdraw the same from the valve stem independently of the piston rod.

JAMES HAMILTON MILLER.
